MATCH BOX SUPPORT

David O. Ford, Petersburg, Va., assignor of one-half to Joseph Mills Hanson, Colonial Heights, Va.

Application February 5, 1940, Serial No. 317,439

3 Claims. (Cl. 248—206)

This invention relates to match holders or supports and more particularly to a holder especially designed for supporting a looped match book of the construction shown in my prior patent issued 5 to me on the 12th day of December, 1939, under No. 2,183,096.

The object of the invention is to provide a match book holder of simple and inexpensive construction, capable of being readily attached to 10 the windshield of an automobile or to a wall, desk stand or other surface and which will hold a book of matches in convenient position to permit selective detachment and ignition of the matches when desired.

15 A further object of the invention is to provide a holder comprising a body portion adapted to receive and support a book of matches and provided with oppositely disposed terminal hooks for detachable and pivotal engagement with a pair of suction cups, one of said suction cups constituting a pivot for the adjacent hooked end of the body portion when the other hooked end thereof is swung upwardly to permit placement and removal of a book of matches.

20 A further object is to form the body portion with an intermediate thickened portion, the upper edge of which is sloped or beveled rearwardly for contact with the attached or stapled ends of the match splints, thereby to force said attached ends outwardly and the tips of the matches rearwardly so as to facilitate grasping and detaching the 25 matches and also to assist in preventing the securing staples from tearing out during severance of said matches.

30 A still further object of the invention is generally to improve this class of devices so as to increase their utility, durability and efficiency.

In the accompanying drawing forming a part 35 of this specification and in which similar numerals of reference indicate corresponding parts in all the figures of the drawing:

Figure 1 is a front elevation of a match book support constructed in accordance with the present invention showing the same in position on the 40 windshield of an automobile,

Figure 2 is a vertical sectional view,

Figure 3 is a front elevation showing one end of the body portion swung upwardly with one of the suction cups as a pivot to permit placement 45 or removal of a book of matches therefrom,

Figure 4 is a front elevation of the support or body portion detached,

Figure 5 is a top plan view,

Figure 6 is a vertical sectional view taken on 50 the line 6—6 of Figure 4, and

Figure 7 is a detail perspective view illustrating a modified form of the invention.

The improved device forming the subject-matter of the present invention is principally designed for supporting a book of matches 5 of the 5 type shown in my prior patent, No. 2,183,096, issued December 12, 1939, and in Figure 1 of the drawing, I have illustrated such a match book in position on the holder to permit successive detachment therefrom of the match splints when 10 desired.

The device comprises an elongated body portion or support 6 formed of plastic or other suitable material and having an intermediate thickened portion 7 projecting laterally from the front face 15 thereof and on which the match book is supported, said thickened portion being provided with a smooth unobstructed surface for the display of advertising matter if desired. The opposite ends of the body portion are relatively thin 20 and the material at said thin portions cut away to form depending hooks 8 adapted to engage the reduced necks 9 of suitable suction or vacuum cups, indicated at 10, for the purpose of supporting the holder on the windshield of an automobile or other surface. The hooks 8 open downwardly and the walls of the body portion are gradually curved upwardly in the direction of the open ends of the hooks, as indicated at 11, so as to provide a clearance and permit the body 25 portion to be swung upwardly with one of the suction cups as a pivot when it is desired to position a match book on or remove a match book from the holder. The lower edge of the thickened portion 7 is preferably rounded, at 12, to assist in 30 preventing cutting the cover of the match book, and this curved edge 12 gradually merges into the upwardly curved portions 11 of said body portion, as best shown in Figure 4 of the drawing. The upper edge of the thickened portion 7 is inclined or beveled rearwardly, as indicated at 13, 35 for contact with the attached or stapled ends of the match splints thereby to force said attached ends outwardly and the fulminate tips rearwardly to facilitate grasping and detaching the 40 matches and also to assist in preventing the securing staple of the match book from tearing out during severance of said matches, as best shown in Figure 2 of the drawing. The suction cups 10 are provided with enlarged heads 14 which 45 contact with the outer faces of the hooks 8 and thereby hold said hooks in engagement with the reduced necks of the suction cups.

In operation, the suction cups are pressed against a windshield or other smooth supporting 50

surface and the hooks 8 forced downwardly in engagement with the necks of said cups. In positioning a match book on the device, one end of the body portion is detached from one of the 5 suction cups and swung upwardly to the position shown in Figure 3 of the drawing with the other suction cup as a pivot. The looped match book is then slipped over the free end of the body portion and moved longitudinally thereof until it is 10 centered over the thickened portion 7, after which the free end of the body portion is swung downwardly on its pivotal axis until the hook at the free end thereof engages the adjacent suction cup when the book of matches will be supported on said body portion in upright position, 15 as previously stated. The intermediate thickened portion 7 not only serves to reinforce and strengthen the body portion but also tends to fill in the space between the adjacent faces of the 20 cover of the book so as to prevent sliding or slipping of the book thereon. Owing to the fact that the upper edge of the thickened portion 7 slopes rearwardly, the cover of the match book by contact therewith forces the heads of the 25 matches rearwardly, thereby setting up a tension which tends to hold the matches in a steady upright position so as to permit selective detachment and ignition of the matches when desired. It will also be noted that, inasmuch as the body 30 portion is spaced from the windshield or other surface to which it is attached by the suction cups, a pocket will be formed at the rear of said body portion for the reception of cards and the like. It will further be noted that the free ends 35 of the hooks are curved or rounded, at 15, to prevent cutting the suction cups, and, if desired, these curved ends may be beveled or made somewhat thinner than the main body of the hooks to facilitate engagement and disengagement of the hooks with the necks of the suction cups.

40 In Figure 7 of the drawing, there is illustrated a modified form of the invention showing how the support can be used in connection with an ash tray. In this form of the device, there is provided an upstanding bracket 16 having its 45 lower end secured in any suitable manner to an ash tray 17 and its upper end provided with a depending supporting flange 18. Secure to the flange 18 by screws or similar fastening devices 50 is a transverse supporting bar having terminal circular heads 21 provided with smooth flat faces against which the suction cups 10 may be pressed for the purpose of supporting a book of matches on said bar. If desired, however, this supporting

bar may be secured to a desk or wall or wherever it is desired to provide a smooth support for the suction cups. When the book of matches is not in position on the body portion 7, any suitable advertising matter thereon will be effectually 5 displayed and when the book is in position on said body portion, said advertising matter may be displayed on the exposed surface of the book so as to be visible at all times.

It will, of course, be understood that the holders may be made in different sizes and shapes and constructed of any suitable material without departing from the spirit of the invention.

Having thus described the invention, what is claimed as new is:

1. A device of the class described comprising an elongated body portion having an intermediate thickened portion adapted to receive and support a book of matches and thin end portions forming hooks disposed at opposite sides of the 20 thick intermediate portions and opening downwardly, the lower edges of the thin end portions being curved in the direction of the open ends of the hooks, and suction supporting cups having outstanding portions, the hooks being detachably 25 engaged about the outstanding portions of the cups, one of said suction cups forming a pivot for the hook at one end of the body portion when the hook at the other end thereof is detached from the adjacent cup and the body portion 30 swung laterally to permit placement or removal of said book of matches.

2. A device of the class described comprising a support having an intermediate thickened portion adapted to receive a looped book of matches 35 and provided with terminal downwardly opening hooks at opposite sides of the thickened portion, and suction supporting cups engaging said hooks, the upper edge of the intermediate thickened portions being inclined rearwardly and adapted 40 to engage the cover of the book at the attached ends of the matches for forcing said attached ends outwardly and the tips of said matches rearwardly.

3. As a new article of manufacture, a match book holder comprising an elongated body portion 45 having its intermediate portion thickened and formed with front and rear faces, the opposite ends of the body portion being of reduced thickness and formed with recesses leading from their lower ends to form downwardly opening 50 hooks for engagement with supports.

DAVID O. FORD.
